UNITED STATES PATENT OFFICE.

ANGELO M. TOZZI, OF BAYONNE, NEW JERSEY, ASSIGNOR TO TOZZI MANUFACTURING COMPANY, OF NEW YORK, N. Y., A CORPORATION OF NEW YORK.

MACHINE FOR UNITING SECTIONS OF CORK AND THE LIKE.

1,274,216.

Specification of Letters Patent. Patented July 30, 1918.

Application filed June 27, 1917. Serial No. 177,840.

To all whom it may concern:

Be it known that I, ANGELO M. TOZZI, a subject of the King of Italy, and resident of Bayonne, in the county of Hudson and State of New Jersey, have invented certain new and useful Improvements in Machines for Uniting Sections of Cork and the like, of which the following is a specification.

The object of this invention is to provide a machine of simple and efficient construction for expeditiously uniting a plurality of contiguous bars or sections of cork and the like, and more especially the sections which are employed in the production of buoyant panels of life preservers.

The invention generally stated, comprises in a machine for the purpose mentioned, means for feeding successive rows of parallel skewers; means for supporting a plurality of juxtaposed sections of material transversely of and beyond the end of the row of skewers, and means for effecting between said row and sections a relative movement longitudinally of the skewers, whereby the sections are fastened securely together by the row of skewers. The term "skewers" is used in a broad sense to comprehend fastening pins, rods and analogous devices.

The invention, more specifically, comprises such a machine having means for longitudinally driving the rows of skewers in succession, and means for clamping the juxtaposed sections transversely of the path of the skewers in their longitudinal movement.

The invention also comprises various features of construction and combinations of parts which will be hereinafter described and claimed.

In the drawings—

Figure 1 is a plan of a machine embodying the principle of my invention; the juxtaposed cork sections being indicated and the skewer inserting mechanism being shown as retracted preparatory to the insertion of the skewers into the sections.

Fig. 2 is a vertical section of the machine as on the line 2—2 of Fig. 1.

Fig. 3 is a sectional view of a portion of the bed, and adjuncts, in the region of the inserting mechanism, showing the cork-sections as assembled and clamped upon the bed, and the skewers as driven into the sections.

Fig. 4 is a transverse vertical section 55 through the machine, as on the line 4—4 of Fig. 2.

Fig. 5 is a sectional detail of one of the channeled skewer-guides, the adjacent feeder chute therefor, and a portion of the slotted transfer plate between the guide and chute, the said plate being shown in its position of delivery to the skewer guides.

Fig. 6 is a perspective view of the slotted transfer plate and the up-standing cam 65 member thereon.

Fig. 7 is a similar view of the plunger head and its pins.

Fig. 8 is a similar view of the channeled guide plate for the skewers. 70

Fig. 9 is a front end view of one of the plunger pins, enlarged.

Fig. 10 is a sectional elevation thereof, showing the opposing end of a skewer.

Referring to the drawings, 10 designates 75 a bed or table and 11 standards therefor, the whole constituting a substantial supporting frame.

Leading to the top of the bed, near one end thereof, is a horizontal trough 12 by 80 way of which a plurality of cork sections, assembled side by side, may be manually fed upon the bed so as to extend transversely of the latter; said bed being provided with a suitably-located transverse bar 13 which 85 affords a guide and backer for the sections (a) imposed on the bed. In the present instance three cork sections are illustrated, but, of course, the number of sections may be varied to meet the requirements of any 90 particular size or type of life preserver.

Overhanging the portion of the bed on which the cork sections are disposed are spaced arms 14 which are pivoted at their outer ends to brackets 15 on the bed; such 95 arms being rigidly connected by cross-rods 16, 17, the forward one of which is preferably arched to constitute a handle. On the underside of each of the arms are spaced teeth 18 which are arranged to engage the 100 tops of the respective cork sections on the bed when the arms are depressed, said arms being maintained normally raised above the sections by the action of suitable springs 19 interposed between the respective arms and 105 the bed.

The cross-rod 17 is connected by means of a link 20 with a foot treadle 21 which

is pivotally supported between the standards, whereby when the treadle is depressed the arms 14 and their teeth are forced down upon the assembled cork-sections so as to 5 clamp the sections firmly in place on the bed. When the treadle is released the arms are permitted to resume their elevated condition.

22 designates a power-driven shaft having 10 its bearings in suitable boxes beneath the bed. In the present instance the shaft is adapted to be driven from a suitably-disposed electric motor 23 through the belt 24 and pulleys 25, 26 on the motor shaft 27 and 15 shaft 22 respectively.

The pulley 26 is loosely mounted on its shaft and a suitable clutch is provided whereby the pulley can be temporarily locked on the shaft. The clutch herein illustrated 20 is an ordinary type of pin clutch which is manually operated to lock the pulley on the shaft but is automatically actuated to release the pulley at the end of a complete rotation of the shaft. The clutch 25 comprises a circumferentially grooved member 28 keyed on the shaft adjacent the hub of the pulley. This member is provided with a slidable key 29 which is movable toward and from the proximate face of the pulley 30 hub; the key being normally pressed toward and into a facial slot 30 in the hub by a suitably-disposed spring 31. The outer edge of the key extends into the circumferential groove of the member 28 and is provided 35 therein with a notch 32 which is located in the path of the inner beveled portion 33 of a hand lever 34. This lever is conveniently pivoted to one of the standards, and it is normally maintained with its beveled portion 40 positioned within the notch of the key by means of a retracting spring 35 which is secured to the inner lever arm and to the adjacent standard. The beveled portion of the lever thus acts as a lock to hold the 45 key retracted against the force of the spring 31. When, however, the outer or handle arm of the lever is depressed by the operator the beveled portion is raised from the key, thus releasing the latter and permitting the spring 50 31 to project the end of the key into the opposing slot in the pulley hub and lock the pulley on the shaft. Thereupon the shaft is rotated by the pulley. The lever being released by the operator its beveled 55 portion rests upon the floor of the groove in the clutch member during the movement of the shaft, and as the shaft completes its rotation the notch of the key receives the beveled portion of the lever which, exerting 60 a cam action on the key, automatically retracts the key in opposition to the force of the spring; thereby releasing the pulley hub from the shaft. Preferably the clutch member on the pulley shaft is provided with a 65 brake band 36 which insures the instant

stopping of the shaft when the pulley is released.

The form of clutch and brake above described is old. It has been selected herein for the purpose of illustration only.

Mounted in and between suitable parallel guides 37 extending longitudinally of the bed is a plunger head 38 which is connected by a pitman 39 with a crank 40 on the shaft 22, which head is thus reciprocated longitudinally of the bed during the rotation of the shaft. On the forward (or right hand) end of the head are a series of forwardly projecting pins 41 which are arranged in spaced parallel relation to each other. In 70 the present instance, four equally spaced pins are employed, but of course the number may be increased or reduced if desired.

42 designates a guide member fastened to the bed directly in front of the cross-head, which member comprises a base plate having a series of up-standing projections 43 extending longitudinally of the bed. The projections correspond in number and spaced relation with the plunger pins and are provided in their upper surfaces with longitudinal channels 44 which receive the respective pins when the plunger is advanced. The basal portions of the channels are semi-circular or substantially so, correspondingly with the curvature of the skewers to be inserted into the assembled sections, and the sides of the channels are outwardly inclined or flared, as seen in Fig. 5. The acting ends of the plunger pins are shaped to correspond with and fit snugly in the lower portions of the guide channels 44, and are provided with tapering sockets 45 the walls of which are adapted to engage and encompass the opposing ends of the skewers which have 90 been seated in the channels as below described, thereby effecting and maintaining a positive central abutment of the plungers against the skewers as the latter are driven along the channels by the plungers. (See 100 Figs. 9 and 10.)

Supported above the guide member by means of brackets 46 on the bed, is a hopper or magazine 47 of suitable shape and dimensions to contain a quantity of skewers 115 (B) in parallel relation to each other and longitudinally of the bed. In the present instance this hopper comprises, in the main, sides, ends and a bottom. Entering the bottom are the upper ends of a series of depending chutes 48 which overhang the channeled guide member, such chutes corresponding in number and spaced relation with the channels of the guide member, and the lower ends of the chutes terminating slightly 120 above and laterally of the channels. The side walls of portions of the chutes within the hopper are inclined as at 49, to afford enlarged inlets to the chutes, the adjacent upper ends of succeeding chutes being con- 130

nected by bridge pieces 50 which insure the delivery of the skewers to the inlets of the chutes. Each of the chutes is of a width and length to permit the downward passage 5 of a single row of skewers in horizontal parallel relation to each other. In order to prevent the tipping or canting of the skewers within the chute, the body of the chute is slightly curved laterally, as at 51, 10 the curved portion terminating in the lower vertical discharge portion 52 of the chute.

Interposed between the guide member and the lower ends of the chutes is a reciprocable plate 53 having therein a series of 15 spaced parallel slots 54 which correspond in number and position with the chutes. The plate (which is shown detached in Fig. 6) is slightly thicker than a skewer, and each of the slots corresponds in width and 20 length with the delivery opening of the chute. When the plate is in one position of its movement the slots thereof are in registry with the delivery ends of the chutes and hence the lowermost skewer in each of 25 the chutes drops into the subjacent slot. When the plate is in the other position of its movement the slots are in registry with the flaring mouths of the channels 44 of the guide member, and hence the skewers, previously entered in the slots, are moved about 30 and transferred to the channels, the body of the plate at such time temporarily closing the ends of the chutes.

In the present instance the slotted trans- 35 fer plate is maintained yieldingly in a position with its slots in registry with the respective chutes by means of springs 55 at one end of the plate. These springs, encircling end guide pins 56 on the plate, press 40 against the plate and a suitably-disposed bracket 57 through which the pins freely extend. On the plate is an upstanding bar 58 having a beveled or cam surface against which impinges the side of a rearwardly ex- 45 tending arm 59 on one of the swinging arms 14 when the latter are depressed in the clamping operation. Thus the transfer plate is moved against the action of the springs 55 so as to position the slots in reg- 50 istry with the guide channels concurrently with the operation of clamping the cork sections on the bed.

The operation of the machine above de- 55 scribed is briefly as follows: A series of cork sections (a) for a life preserver panel are manually arranged side by side in the trough 12, and the whole then shifted to and upon the top of the table and in contact with the backer bar 18, as seen in Figs. 1, 2 60 and 3. The operator then depresses the treadle, thus lowering the toothed arms 14 upon the assembled sections and firmly clamping the latter in position. At the same time the arm extension 59 cooperates 65 with the upstanding cam bar 58 to shift the

slotted plate 53 transversely of the bed. The series of skewers contained in the slots of this plate are thus transferred to and seated in the stationary guide channels 44. The operator, holding the treadle depressed, 70 pushes down the handle portion of the lever 34, thus unlatching the key 29 and permitting its engagement with the slotted face of the pulley hub, thereby locking the pulley on the shaft 22. Upon the completion 75 of a rotation of the shaft the key is automatically cammed back by the beveled portion of the lever, thus unlocking the pulley, whereupon the shaft is instantly arrested by the action of the brake. During the ro- 80 tation of the shaft the plunger head 38 is reciprocated, the pins thereof in their move- 85 ment into and through the parallel chan- nels of the guide member 42 forcing the skewers which are seated in said channels into and transversely of the assembled cork sections, thereby fastening the latter securely together. In the return stroke of the plunger the pins are retracted, whereupon the operator releases the treadle, and removes the 90 united cork sections from the machine. He then assembles another series of cork sec- 95 tions upon the bed preparatory to a repetition of the operation above described.

It is to be understood that my invention 95 is not limited to the details of construction disclosed, as the same may be variously modified within the principle of the invention and the scope of the appended claims.

I claim—

1. In a machine of the character described, the combination with a skewer-containing hopper and means for supporting a row of skewers in parallel relation to each other, of a movable element for receiving consecutive rows of skewers from the hopper and transferring them to said supporting means, means for supporting a plurality of juxtaposed sections of material transversely of and beyond the end of the skewers in said 100 supporting means, means for clamping the positioned sections, co-acting means between said movable element and the clamping means whereby said element and clamping means are simultaneously operated, and 105 means for effecting between each supported row of skewers and the positioned sections a relative movement longitudinally of the skewers.

2. In a machine of the character described, the combination of an element having a row of spaced parallel guide channels, means for feeding successive rows of skewers to said channels, a reciprocative element having pins corresponding with and longitudinally mov- 110 able in said channels, means for reciprocating said element, means for supporting a plurality of juxtaposed sections of material transversely of and adjacent the delivery end of the channels, and means, including 115 120 125 130 135

- movable clamping members, for temporarily locking the positioned sections upon said supporting means.
3. In a machine of the character described, the combination of a supporting bed, an element thereon having a row of spaced parallel guide channels, means for feeding successive rows of skewers to said channels, a reciprocative element including pins corresponding to and longitudinally movable in said channels, means for reciprocating said element, and means for clamping on the bed transversely of and adjacent the delivery end of the channels a plurality of juxtaposed sections of material.
4. In a machine of the character described, the combination of a skewer-containing hopper, a series of skewer-feeding chutes depending therefrom, an element having a row of parallel guide channels corresponding to but out of vertical alinement with said chutes, a transfer member having a series of transverse slots corresponding to the chutes, means for reciprocating said transfer member so as to move its slots from the chutes to the guide channels and back again, and thereby transfer succeeding rows of skewers from the chutes to the guide channels, means for longitudinally moving each row of skewers along the channels, and means for supporting a plurality of juxtaposed sections of material transversely of the path of the skewers in their longitudinal movement.
5. In a machine of the character described, the combination of a skewer-containing hopper, a series of skewer-feeding chutes depending therefrom, an element having a row of parallel guide channels corresponding to but out of vertical alinement with said chutes, a transfer member having a series of transverse slots corresponding to the chutes, means for reciprocating said transfer member so as to move its slots from the chute to the guide channels and back again, and thereby transfer succeeding rows of skewers from the chutes to the guide channels, means for longitudinally moving each row of skewers along the channels, a support for a plurality of juxtaposed sections of material transversely of the path of the skewers in their longitudinal movement, and means for clamping said sections on the support.
6. In a machine of the character described, the combination of a skewer-containing hopper, a series of spaced skewer-feeding chutes depending therefrom, an element having a row of spaced parallel guide channels corresponding to but out of vertical alinement with said chutes, a transfer member having a series of spaced transverse slots corresponding to the chutes, means for reciprocating said transfer member so as to move its slots from the chutes to the guide channels and back again, and thereby transfer succeeding rows of skewers from the chutes to the guide channels, means for reciprocating said transfer member including pins corresponding to and longitudinally movable in said channels, and means for clamping on the bed transversely of and adjacent the delivery end of the channels a plurality of juxtaposed sections of material.
7. In a machine of the character described, the combination of a skewer-containing hopper, a series of spaced skewer-feeding chutes depending therefrom, an element having a row of spaced parallel guide channels corresponding to but out of vertical alinement with said chutes, a transfer member having a series of spaced transverse slots corresponding to the chutes, means for reciprocating said transfer member so as to move its slots from the chutes to the guide channels and back again, and thereby transfer succeeding rows of skewers from the chutes to the guide channels, a pin-bearing plunger for longitudinally moving each row of skewers along the channels, a shaft, a positively driven-pulley loose thereon, a clutch, means for manually operating said clutch to lock the pulley to the shaft and to permit the automatic release of the pulley upon the completion of a revolution, operative connection between the shaft and the plunger, and means for supporting a plurality of juxtaposed sections of material transversely of the path of the skewers in their longitudinal movement.
8. In a machine of the character described, the combination of a skewer-containing hopper, a series of spaced skewer-feeding chutes depending therefrom, an element having a row of spaced parallel guide channels corresponding to but out of vertical alinement with said chutes, a transfer member having a series of spaced transverse slots corresponding to the chutes, means for reciprocating said transfer member so as to move its slots from the chutes to the guide channels and back again, and thereby transfer succeeding rows of skewers from the chutes to the guide channels, a pin-bearing plunger for longitudinally moving each row of skewers along the channels, a shaft, a positively driven-pulley loose thereon, a clutch, means for manually operating said clutch to lock the pulley to the shaft and to permit the automatic release of the pulley upon the completion of a revolution, operative connection between the shaft and the plunger, and means for supporting a plurality of juxtaposed sections of material transversely of the path of the skewers in their longitudinal movement.
9. In a machine of the character described, the combination of a skewer-containing hopper, a series of spaced skewer-feeding chutes depending therefrom, an element having a row of spaced parallel guide channels corresponding to but out of vertical alinement with said chutes, a transfer member having a series of spaced transverse slots corresponding to the chutes, means for reciprocating said transfer member so as to move its slots from the chutes to the guide channels and back again, and thereby transfer succeeding rows of skewers from the chutes to the guide channels, a pin-bearing plunger for longitudinally moving each row of skewers along the channels, a shaft, a positively driven-pulley loose thereon, a clutch, means for manually operating said clutch to lock the pulley to the shaft and to permit the automatic release of the pulley upon the completion of a revolution, operative connection between the shaft and the plunger, and means for supporting a plurality of juxtaposed sections of material transversely of the path of the skewers in their longitudinal movement.

means for reciprocating said transfer member so as to move its slots from the chutes to the guide channels and back again, and thereby transfer succeeding rows of 5 skewers from the chutes to the guide channels, a pin-bearing plunger for longitudinally moving each row of skewers along the channels, a shaft, a positively driven-pulley loose thereon, a clutch, means for manually 10 operating said clutch to lock the pulley to the shaft and to permit the automatic release of the pulley upon the completion of a revolution, operative connection between the shaft and the plunger, a support for a 15 plurality of juxtaposed sections of material transversely of the path of the skewers in their longitudinal movement, clamp members overhanging the said support, a treadle, and operative connection between said treadle and the clamp members. 20

10. In a machine of the character described, a skewer-containing hopper and a series of spaced skewer-feeding chutes depending therefrom, each of said chutes being internally proportioned to permit the 25 descent therethrough of a single row of skewers in horizontal parallel relation to each other, and being laterally curved above the delivery end of the chute to present curved walls to the longitudinal sides of 30 each of the descending skewers and thus prevent the tipping of the skewers.

Signed at New York in the county and State of New York this 25th day of June, A. D. 1917.

ANGELO M. TOZZI.
